UNITED STATES PATENT OFFICE.

SARA E. WEAVER, OF CARLISLE, PENNSYLVANIA.

REIN-GUIDE.

1,003,678.

Specification of Letters Patent. Patented Sept. 19, 1911.

Application filed November 15, 1910. Serial No. 592,554.

To all whom it may concern:

Be it known that I, SARA E. WEAVER, a citizen of the United States, residing at Carlisle, in the county of Cumberland and State 5 of Pennsylvania, have invented a new and useful Improvement in Rein-Guides, of which the following is a specification.

This invention relates to certain new and useful improvements in guides, the object being to provide a rein guide which is exceedingly simple and cheap in construction, and one which can be readily attached to the harness in such a manner that the rein will be supported so that all danger of the reins 10 dropping down under the horse's feet is prevented.

Another object of my invention is to provide a rein guide which is so constructed that all danger of the horse's tail becoming 15 entangled in the guide is prevented.

A still further object of my invention is to provide a guide which is formed with a pair of guide loops which are so constructed that they can be opened in order to place a rein 20 therein.

Another object of my invention is to provide a rein guide in which the guide loop is formed of a strap of leather which carries a snap hook which is connected to an eye carried by the strap.

With these objects in view, the invention consists in the novel features of construction, combination and arrangement of parts hereinafter fully described and pointed out in 25 the claim.

In the drawing forming a part of this specification:—Figure 1 is a perspective view of my improved rein guide showing the application of the same. Fig. 2 is a detail 30 elevation partly in section.

In carrying out my improved invention, I employ a strap A which is riveted centrally to the dock of the crupper by a rivet B as clearly shown, and said strap has a ring C secured thereon to each side of its center by 45 a strap E which is secured upon the strap A by a rivet F as clearly shown. Carried by each end of the strap A is a snap hook G which is secured to the end by forcing the end of the strap through the loop of the 50 snap hook and bending the strap back upon itself and securing the same by a rivet as clearly shown. Each of said snap hooks are adapted to engage a ring C so as to form a loop through which the respective rein is 55 adapted to pass in such a manner that the reins will be held up in position upon the back of the animal.

It will be seen that by providing a rein guide of leather in which the loops are 60 opened and closed by a snap loop, all danger of the horse's tail being caught by the same is prevented, and at the same time an exceedingly simple and neat appearing guide is formed.

65 What I claim is:—

The combination with a crupper dock, of a flexible strap arranged transversely thereupon, and secured thereto midway the ends of the strap, rings secured to the upper 70 face of the strap and upon opposite sides of the crupper dock and means carried by the free ends of the strap for detachably engaging said rings.

SARA E. WEAVER.
